UNITED STATES PATENT OFFICE

LOUIS ILDEVERT POIRMEUR, OF MERU, FRANCE

ROTARY PUMP OF THE OSCILLATING-BLADE TYPE

Application filed September 25, 1929, Serial No. 395,139, and in France October 5, 1929.

My invention relates to that type of rotary pumps or compressors wherein a rotor is adapted to rotate eccentrically in the bore of a stator, while remaining tangent to the wall 5 of said bore; the space comprised between the stator and the rotor, into which open the suction and exhaust ports, being swept by oscillating blades pivotally secured to the rotor. In this type of pumps there is generally provided along the generatrix of contact between the rotor and the stator a fluid tight packing borne by the latter with a view to prevent any communication between the suction and exhaust pipes.

15 My invention has for its particular object improvements in rotary pumps showing the above disclosed features. Said improvements consist chiefly in the arrangement on the rotor of the devices adapted to provide 20 fluid tightness between the rotor and the stator, whereby said devices rotate integral- 25 ly with the rotor. Among other advantages, this does away with all parasitical friction and allows, owing to the multiplication of the packing elements and the movement im- 30 parted thereto, a constant shifting of said elements. Therefore, the pumps constructed according to my invention, are adapted for carrying water or any other liquid holding 35 in suspension solid particles or material such as sand, earth and the like. The packing elements are preferably constituted by pivoting parts, hingedly secured to the rotor in a manner similar to the operating blades but open- 40 ing in the direction opposed to that of said blades. The outer cylindrical surface of these parts is preferably leather coated so as to improve the fluid tightness between the said surface and the wall of the stator.

45 I have described hereinbelow and shown on accompanying drawings a form of my invention:

Fig. 1 is a diagrammatical view of a pump showing the essential features of the invention.

50 Figs. 2 and 3 are a vertical and a horizontal cross-section of a pump to which the improvements have been applied.

I have assumed in the example shown that the pump is to rotate in a predetermined di-

rection. It carries four oscillating blades, but obviously the number of blades is immaterial.

As stated hereinabove, the essential feature of my invention consists in that the fluid-tight packings to be interposed between the stator 1 and the rotor 2 for separating the fluid suction pipe 3 and the fluid outlet pipe 4, are carried by the rotor with which therefore they revolve. To this end, the rotor 2 is provided between two consecutive blades, with a cylindrical shutter 6 pivotally secured to said rotor along a generatrix. The shutter is disposed in a manner such that it opens in a direction opposed to that of the rotor blades 5 (Fig. 1). It is provided on its outer surface, with a leather packing 7 similar to that provided on the blades. Thus, when the shutter arrives near the contacting generatrix or line of tangence of the stator with the rotor, the pressure of the fluid causes it to bear against the said stator whereby it provides the desired watertight separation between the suction and outlet chambers.

In the example shown, each blade 5 is disposed with its corresponding shutter 6 in a lateral recess formed in the wall of the rotor 2; the blade and shutter are pivoted to the ribs 8 appearing thus on the surface of the rotor. A chamber 9 may be provided inside the rotor 2, underneath the blades 5 and shutter 6 so as to reduce the weight of the rotating parts and to allow compensation between the pressures exerted on either side of the blades and shutters.

In the case where the pump is to operate indifferently in both directions, I give the same peripheral width to the blades and to the shutters so that the blades may when desired act as shutters and reversely. The rotor 2 may be provided with lateral leather cheeks or the like ensuring lateral fluid tightness in cooperation with the flanges closing the stator 1.

Inside the stator bore are provided grooves 10 starting from the suction and outlet pipes 3 and 4 and extending from the axis of said pipes over an angular distance of about 90°. Instead of providing these grooves in the stator 1, I may use a lining for the stator the

cylindrical wall of which is provided with slots playing the part of the said grooves. Either of these arrangements allows the pipes 3 and 4 to be at 90° from one another as shown.

5. What I claim is:

1. A rotary machine comprising a bored stator, a rotor adapted to rotate eccentrically inside the stator bore and to remain in contact with the wall thereof along a predetermined generatrix, a fluid inlet and a fluid outlet on either side of said generatrix, a series of blades pivotally secured to the rotor and adapted to open in a given direction and 10 to come into contact with the wall of the bore and a series of cylindrical shutters provided with a yielding cover at their outer edge pivotally secured to the rotor and adapted to rotate in the opposite direction and to come 15 into fluid-tight engagement with the wall of the bore throughout the length thereof when they arrive near the generatrix of contact of the stator bore.

2. In a rotary machine the combination of 25 a bored stator, a rotor adapted to rotate eccentrically inside the stator bore and provided with a series of radial recesses, a series of blades and of shutters pivotally secured to the rotor at the outer edges of the said 30 recesses and adapted to come into engagement with the wall of the stator bore, the blades and shutters opening in opposite directions respectively away from the rotor and the shutters providing a fluidtight closure be- 35 tween the chambers formed between the chambers formed between the rotor and the stator on either side of the generatrices thereof which are the nearest one to the other.

3. In a rotary machine as claimed in claim 40 2, yielding flanges at either end of the rotor adapted to frictionally engage the wall of the stator bore.

4. In a rotary machine the combination of 45 a bored stator, a rotor adapted to rotate eccentrically inside the stator bore and provided with a series of radial recesses, a series of blades and of shutters pivotally secured to the rotor at the outer edges of the said recesses and adapted to come into engagement 50 with the wall of the stator bore, the blades and shutters opening in opposite directions respectively away from the rotor and both adapted to provide a fluid tight closure be- 55 tween the chambers formed between the rotor and the stator on either side of the generatrices thereof which are the nearest one to the other.

5. In a rotary machine as claimed in claim 2 the provision on either side of the fluid- 60 tight closure of a fluid inlet and a fluid outlet respectively and grooves formed on the stator bore wall and extending from said inlet and outlet to a point of an angular distance of substantially 90° beyond same.

6. In a rotary machine as claimed in claim

2 the provision on either side of the fluidtight closure of a fluid inlet and a fluid outlet re- 70 spectively, a slotted lining for the stator bore, the slots therein extending from said inlet and outlet to a point at an angular distance of substantially 90° beyond same.

In testimony whereof I affix my signature.
LOUIS ILDEVERT POIRMEUR.
